THOMAS NESOM, OF INDIANAPOLIS, INDIANA.

FOLDING BABY-HAMMOCK.

1,161,405.

Specification of Letters Patent.

Patented Nov. 23, 1915.

Application filed October 13, 1913. Serial No. 794,945.

To all whom it may concern:

Be it known that I, THOMAS NESOM, a citizen of the United States, residing at Indianapolis, in the county of Marion and State of Indiana, have invented a new and useful Folding Baby-Hammock, of which the following is a specification, reference being had to the accompanying drawings and to the letters and figures of reference 10 marked thereon.

This invention relates to hammocks having folding frames and supports and has reference more particularly to a safety hammock that is adapted for comfortably holding babies and which may be conveniently carried about from place to place.

An object of the invention is to provide an improved hammock that shall be so constructed as to be adapted to be folded conveniently for shipment or to be carried on trips accompanied by children, especially when picnicking or attending lawn parties.

Another object of the invention is to provide improved folding hammock supports that shall be so constructed as to be adapted to be conveniently set up for use and which may be variously arranged as may be desired, and which shall be reliable and durable in use.

With the above mentioned and other objects in view, the invention consists in a hammock frame of novel construction comprising folding sections, and novel sectional supporting legs detachably connected to the frame, the invention consisting further in the parts and combinations and arrangements of parts as hereinafter particularly described and claimed.

Referring to the drawings, Figure 1 is a side elevation of the improved hammock arranged to be supported on the ground; Fig. 2, an end elevation of the frame and supporting legs; Fig. 3, a top plan of the frame; Fig. 4, a fragmentary section on the line A in Fig. 2; Fig. 5, a fragmentary perspective view of the frame; Fig. 6, an elevation of one of the frame parts; Fig. 7, a top plan of the part shown in the preceding figure 50 partially in section; Fig. 8, an end elevation of the frame and legs slightly modified as to arrangement thereof; Fig. 9, a side elevation of the modified arrangement of the supporting legs; Fig. 10, an elevation of one 55 of the frame members; Fig. 11, a horizontal section of the member shown in the preced-

ing figure, and Fig. 12 is an elevation of one of the leg members.

Similar reference characters in the different figures of the drawings indicate corresponding elements or features of construction herein referred to.

The improved hammock frame comprises two metallic main end parts that comprise arms 1 and 1' respectively that are normally horizontal and having upwardly extending hinging ears 2 and 2' on one end in each of which is a pivot hole 3 to receive a pivot or hinge pin, the arms having also downwardly extending bosses 4 and 4' adapted to be connected to suitable supporting legs, there being shoulders 5 and 5' formed on the bosses respectively. The tops of the shoulders face upward beyond the ends of the arms on a plane corresponding to the bottom of the 75 arm, and the shoulders preferably have upwardly extending lips 6 and 6' on the outer portions thereof. Each boss has a bolt hole 7 therein and also serrations or teeth 8 and 9 on the outer and inner sides respectively 80 and arranged radially around the hole 7. The bosses are provided respectively with securing bolts 10 and 10' each arranged in the hole 7, the bolts having thumb nuts 11 and 11' thereon respectively for securing 85 legs to the bosses. The opposite ends of the arms 1 and 1' are provided with sockets 12 and 12' respectively and also eyes 13 and 13' adjacent to the sockets to which the hammock netting may be connected, the sockets 90 extending at oblique angles from the arms. Two companion end members are provided which comprise arms 14 and 14' having laterally off-set end portions 15 and 15' upon which are hinging ears 16 and 16' respectively, each ear having a pivot hole 17 therein to receive pivot or hinge pins 18 and 18' respectively which connect the ears of the companion members to the main members or parts of the frame above the plane of the 100 frame, the arms of the companion members normally resting upon the shoulders of the main members. The under side of the arms of the companion members has a notch 19 therein to receive a lock for preventing pivotal movement of the connected members. The arms 14 and 14' have obliquely arranged sockets 20 and 20' thereon respectively and are provided also with eyes 21 and 21' respectively to which the hammock 110 netting may be connected. In order to suspend the hammock frame by means of a

rope so that it may swing, the hinging ears 2 and 2' have upwardly extending stems 22 and 22' to which a rope may be connected. The frame comprises also two wooden corner bars 23 and 23' and similar bars 24 and 24'. The bars 23 and 24 are fixedly secured in the sockets 12 and 20 respectively and are provided with sockets 25 and 26 respectively, the bars 23' and 24' being secured in the 5 sockets 12' and 20' respectively and provided with sockets 25' and 26' respectively. The bars 23 and 24 extend divergently from the end members, as do the oppositely arranged bars 23' and 24', the frame comprising also two side bars 27 and 27' provided with sockets 28 and 28' fitted to the 10 sockets 25 and 25' respectively, and sockets 29 and 29' fitted to the sockets 26' and 26 respectively, the planes of the joint faces 15 being at right angles to the side bars. Each socket 25, 25', 26 and 26' is provided with two hinging ears 30 and 30' on the under side thereof embracing a hinging ear 31 provided on the under side of each abutting 20 socket 28, 28', 29 and 29' and connected thereto by means of a hinge pin 32, so that the hinges prevent the side portions of the frame from dropping downward when supported by the end members. The bed fabric 25 or netting 33 is suitably connected to the frame so as to be suspended thereby and permits the frame to be folded into small compass. The frame, as will be seen, is octagonal so that the frame bars may be 30 cheaply formed of straight pieces. The outer sides of the bars 23 and 24 are provided with studs 34 and 35, the opposite bars being similarly provided with studs 34' and 35' to which braces may be connected when 35 supporting legs are used.

The preferred form of supporting appliances comprise two similarly formed legs 36 and 36' provided with sockets 37 and 37' having bosses 38 and 38' thereon respectively, 40 each boss having a bolt hole 39 therein to receive the bolt 10 or 10'. The boss is provided with a locking projection 40 that extends into the notch 19 for preventing relative pivotal movement of the two end members of the frame, the inner side of the boss having radial serrations or teeth 41 adapted to engage the teeth 8 or 9. The opposite ends of the legs are provided with sockets 42 and 42' respectively which have bosses 43 and 43' thereon respectively, each boss 45 being similar to the boss 4 having serrations on opposite sides thereof, the boss being provided with bolts 44 and 44' respectively for securing foot portions or parts 50 to the legs, the bolts having heads 45 and 45' provided with pivots 46 and 46' respectively. Two braces 47 and 48 are provided for each leg and are connected to either pivot and provided with a hook or clasp 49 55 adapted to be detachably connected with a

stud 34 or the like with which the frame is provided. Two foot members 50 and 51 are provided that have sockets 52 and 53 thereon respectively, the sockets being provided with bosses 54 and 55 respectively, 70 each boss being similar to the boss 38, and the two bosses are connected to opposite sides of the boss 43, and secured thereto by means of a thumb nut 56 on the bolt 44 so as to extend divergently downward, the 75 lower ends of the legs being provided with caster frames 57 and 58 provided with rollers 59 and 60 respectively. Similar foot members 50' and 51' are provided with sockets 52' and 53' having bosses 54' and 55' 80 secured to the boss 43' by means of a thumb nut 56', the legs being provided with caster frames 57' and 58' in which rollers 59' and 60' are mounted.

In some cases, each end of the hammock 85 frame is supported by means of two leg members 61 and 62, each member being identically like the leg 36, and the members are secured to opposite sides of the boss 4 or 4' so that their lower ends shall be spread 90 apart, the bosses on the lower ends being provided with bolts 63 and 64 having thumb nuts 65 and 65' thereon, each bolt having the head 45 to which braces may be connected. Two extensions 66 and 67 are secured in sockets 68 and 69 having bosses 70 and 71 respectively that are secured to the bosses of the members 61 and 62 respectively. Socket 68 has a stud 72 thereon, a tie bar 73 being suitably connected to the socket 69 100 and having an aperture 74 therein adapted to receive the head of the stud, a slot 75 extending from the aperture to receive the body of the stud, whereby the legs are prevented from being forced apart.

In practical use, the hammock frame is either suspended by means of a rope or cord, or two of them, or it is supported by means of the legs and may be moved about upon a floor or on the ground as may be desired. 110 When not in use, the securing bolts of the legs are slackened and the various members or parts of the legs are folded together, the hammock frame also being compactly folded so that the whole may be conveniently carried about and may be readily set up for use.

Having thus described the invention, what is claimed as new is—

1. In a folding hammock, a frame comprising two principal portions normally arranged horizontally, each portion being composed of a straight side bar, two straight corner bars normally extending horizontally from opposite ends respectively of the side 120 bar at divergent oblique angles to the side bar, a main end member fixed on the end of one of said corner bars at an oblique angle thereto, a companion end member fixed on the end of the remaining one of the cor- 125 130

- ner bars at an oblique angle thereto, two pivots connecting the companion end members to the main end members respectively above the plane of the frame, two supporting shoulders fixed on the two main end members respectively and extending under the adjacent companion end members respectively, and hinging devices connecting the side bars to the adjacent corner bars.
2. In a folding hammock, the combination of a main end part comprising a normally horizontal arm, an upwardly extending hinging ear fixed on one end of the arm, an apertured stem fixed on the ear, a socket fixed on the opposite end of the arm at an oblique angle thereto, a boss fixed on the arm below the said ear and pivotally connected thereto, and a socket fixed on the opposite end of the arm at an oblique angle thereto; with two frame bars fixedly secured in said sockets respectively, and a leg member engaged by said bolt and said projections.
3. In a folding hammock, the combination of two sockets fitted together, one of the sockets extending at an oblique angle relative to the other, each socket having a hinging ear on the normal under side thereof, a hinge pin connecting the ears of the two sockets together and extending at an oblique angle to the oblique-angled socket and at a right angle to the remaining one of the sockets, and two frame bars fixedly secured in the two sockets respectively.
4. In a folding hammock, the combination of two pairs of end members, the two members of each pair being hinged together and having each a straight frame bar fixed obliquely thereon, each bar having a hinging ear on the normal under straight side thereof, a side bar having two hinging ears that are connected to the ears of the frame bars of two of the end members respectively, and another straight side bar having two hinging ears that are connected to the ears of the frame bars of the remaining two end members.
5. In a folding hammock, the combination of two main end members comprising each an arm having a boss fixed on its under portion and a hinging ear fixed on its upper portion and also a shoulder fixed on and projecting from the boss, the ear having a suspender stem fixed thereon, the arm having also a socket thereon, two companion members having hinging ears fixed thereon pivoted to the hinging ears of the main members respectively, the companion members normally resting on the shoulders respectively and having each a socket thereon, and frame bars fixedly secured in the sockets respectively.
6. In a folding hammock, the combination of two pairs of end members, the two members of each pair being hinged together and having each a straight frame bar fixed obliquely thereon, the bars extending divergently each bar having a stud on the outer side thereof, two side bars hinged to the frame bars of the members of the two pairs thereof, two legs secured to one of the two members of the two pairs respectively, and a plurality of braces, two of the braces being pivotally connected with one of the legs and divergently and detachably connected to two of the studs respectively, two others of the braces being pivotally connected with the remaining one of the legs and divergently and detachably connected to two others of the studs respectively.

In testimony whereof, I affix my signature in presence of two witnesses.
